BIBLE AND SUNDAY SCHOOL DATA HOLDER

Willard Winfred Jones, Fort Lauderdale, Fla.

Application May 3, 1954, Serial No. 427,183

2 Claims. (Cl. 150—1.6)

This invention relates to a pocketed container for books and the like and has as its primary object the provision of a soft, flexible container or cover having a plurality of pockets therein separated by partitions interiorly of the container, each pocket being individually closable by means of a separate fastener such as a zipper or the like.

An additional object of the invention is the provision of means whereby the books contained in the receptacle or cover may be opened to any desired position without the necessity of removing the same from the cover.

A further object of the invention is the provision of such a device which is sufficiently flexible to permit relatively easy handling of the books or other articles contained therein, which is sturdy and durable in construction, which will effectively protect the contents, which is light in weight, and which may be manufactured with a relative minimum of expense and difficulty.

Still other objects reside in the combinations of elements, arrangements of partitions, and features of construction, all as will be more fully pointed out hereinafter and disclosed in the accompanying drawing wherein is shown a perfected embodiment of this inventive concept.

In the drawing:

Fig. 1 is a perspective view of one form of container embodying features of the instant invention.

Fig. 2 is a similar perspective view, but taken from the opposite side thereof.

Fig. 3 is a sectional view taken substantially along the line 3—3 of Fig. 1 on an enlarged scale.

Fig. 4 is a fragmentary view, partially in top elevation and partially in section, showing the container or holder in open position.

Fig. 5 is a fragmentary perspective view, partially sectioned, showing the container in open position, and

Fig. 6 is a fragmentary perspective view of the central partition disassociated from the container.

Having reference now to the drawing in detail, the container of the instant invention, generally indicated at 10, includes a front cover 11 and a rear cover 12 preferably integral with and connected by a back portion 13. Suitably stitched to the back portion 13, as by means of stitching 14, are outwardly extending tabs or flanges 15, comprising the rear end of a central partition 16. The central partition 16 extends forwardly the full length of the front and rear walls 11 and 12, and has secured to opposite sides thereof as by means of stitching 17 the flanged portions 18 of oppositely disposed separable fastener halves 19. The opposite half 20 of each separable fastener is secured to the adjacent front or rear wall as by stitching 21, the arrangement being such that the separate portions 19 and 20 will coact in the customary fashion.

As best shown in Figs. 3 and 4, the outer extremes of both the front and rear cover portions 11 and 12 are inwardly turned, as at 22 and 23 respectively, and slightly stiffened to provide marginal flanges for the ends of the covers.

2

As best shown in Figs. 1 and 2, the separable fastener halves may be extended upwardly as at 19a and 20a to overlie the top of the container and may correspondingly extend downwardly and around the bottom thereof. It will now be readily apparent that any suitable book 25, in the illustrative embodiment shown, the Holy Bible, may be positioned on either side of the partition 16 and opened at any suitable point as indicated at 26 in Fig. 4. Similarly, any additional other book or books, such as text books 27 and 28, may be positioned on the other side of the partition and opened independently of the book 25, by the opening of the zipper adjacent the rear cover portion 12. Conversely, the book 25 may be opened to any suitable place by the opening of its associated zipper, without disturbing the other book or books.

By virtue of the flexibility of the cover member, it is unnecessary to remove any of the volumes for opening at any desired place.

Obviously, the device may be made of any suitable flexible material and in any desired size. Further, the invention is not limited to the two compartments and the central partition, but may be made with three or more compartments as may be desirable or useful.

From the foregoing, it will now be seen that there is herein provided an improved cover for a plurality of books which is light in weight, flexible in construction, and which material facilitates the handling of such books as well as protecting the same, and which accomplishes all of the objects of this invention and others, including many advantages of great practical utility.

As many embodiments may be made of this inventive concept and as many modifications may be made in this embodiment, it is to be understood that all matter hereinbefore shown and described is to be interpreted merely as illustrative and not in a limiting sense.

It is to be understood that this invention relates to a flexible container comprising in one piece a front cover, a rear cover, and a back. This container may be formed from an integral piece of material such as leather or like material. The partition 16 has the T-shaped structure 15 at its inner end which snugly fits the one-piece container at the back thereof, Fig. 2.

I claim:

1. A container construction designed to house books, comprising a front cover and a rear cover, a back portion connecting said front and rear covers, a broad flat, central portion provided at its inner end with outwardly-extending flat integral tabs, said tabs fastened to the inside of said back portion, inwardly-extending flanged portions on opposite sides of said central flat portion and at its front edge and secured thereto, each flanged portion provided with part of a fastener at its outer edge, parts of fasteners secured to the inner face of said front and rear covers and extending inwardly, and all of said fasteners cooperating for securing said container in a closed condition.

2. A container construction designed to house books, comprising a front cover and a rear cover, a back portion connecting said front and rear covers, a central portion of substantially the same size as said front and rear covers, said central portion provided on its rear with integral oppositely extending tabs, said tabs secured to the inner face of said back portion, and means on the front edges of said front cover, rear cover, and central portion for fastening all in a closed position.
